SAFETY DEVICE FOR FIRING MECHANISM

John D. Pedersen, Jackson, Wyo.

Application October 24, 1931, Serial No. 570,826

2 Claims. (Cl. 42—70)

This invention relates to a safety device for the firing mechanism of fire arms adapted for use in all types of trigger-operated fire arms. In its present form, the invention is illustrated for use 5 with a semi-automatic rifle of the type shown in my previous application Serial No. 499,030.

The particular object of the invention is to provide a safety device which, when adjusted to its safe or "on" position, will not only block the 10 firing mechanism from operation but will also give a warning to the marksman which cannot be ignored when he attempts to fire the piece. It frequently happens in competitive target shooting that the marksman, after carefully laying 15 his sights upon the target, will attempt to pull the trigger and then find that he has inadvertently left the safety on, and of course in readjusting the safety for firing he loses his carefully prepared aim and must align his sights over again. Such an objectionable occurrence will be 20 entirely avoided by use of the present safety device which, when in its safe position, provides a portion for extending into the space normally occupied by the finger in pressing the trigger. 25 The marksman therefore will not be able to place his finger properly in position for firing when the safety is "on", and will thereby be warned to throw the safety into "off" position before taking careful aim.

30 Referring to the drawing, which shows a preferred embodiment of the invention,—

Fig. 1 is a side elevation of a firing mechanism mounted on a detachable guard frame of the type shown in my previous application referred to.

35 In this view the safety device is shown in its "off" position.

Fig. 2 is a fragmentary view of the same parts shown in Fig. 1, with the safety device adjusted to its "on" position;

40 Fig. 3 is a detached view of the safety device; Fig. 4 is a detached view of the trigger; and Fig. 5 is a detached view of the firing spring base.

45 Referring more particularly to the drawing, 1 indicates the trigger guard frame adapted to carry thereon the firing mechanism as shown. This trigger guard may be secured to a rifle in the manner shown in my previous application referred to. It will be noted that the firing 50 mechanism herein shown is of the swinging hammer type rather than of the sliding striker type described in the application referred to, but this change in design in no way alters the principle of the safety device as regards its action on the 55 trigger of said firing mechanism.

The trigger guard frame has the usual trigger guard or bowed portion 2 (as shown) surrounding the trigger, indicated at 3. The trigger is pivotally mounted on the trigger pin 4, and a forward extension 5 of said trigger is articulated 60 within the forked rear end 6 of a sear 7, which sear is pivotally mounted on the sear pin 8. The sear nose or hook 9 is adapted to engage the notch 10 of the hammer 11 pivoted on the hammer pin 12. An escapement pawl 13 is pivotally 65 carried on the sear 7 and is controlled by a pawl spring 14 for suitable escapement action with respect to arm 15 of the hammer 11. This escapement action is of the well understood sort for the control of single shot firing with a semi-automatic 70 rifle and need not be further described.

The firing spring 16 is mounted upon hammer rod 17, the forward end of which is pivotally connected at 18 to the hammer and the rear end 19 of which extends slidably through 75 the firing spring base 20. It will be understood that the firing spring bears at its rear end against the base 20 and at its forward end against a shoulder on said hammer rod 17, thus tending to rock the hammer for firing. The firing 80 spring base 20 has a lower tongue portion 21 which engages in an undercut notch (not shown) on the pivot pin 22, and also has a rear end 23 which bears downwardly on a shoulder 24 of the trigger, as shown in Figs. 1 and 2. The rear- 85 wardly directed force of the firing spring on the firing spring base 20 tends to rock said base clockwise on its bearing on pivot 22 and thus cause the end 23 of said base to bear downwardly on the shoulder 24 of the trigger to thus return the trigger to its normal position after being pulled, similarly to the usual trigger spring action.

The safety device 25 (shown more clearly in Fig. 3) is pivoted on the pin 22 and has a projecting nose 26 which bears against cam surface 27 on the firing spring base in such a manner that the safety device will be yieldingly held in each of its two set positions,—the "off" position shown in Fig. 1, and the "on" position 95 shown in Fig. 2. When the safety device is turned to its "on" position, it brings a shoulder 28 of its upper portion in blocking relation to a shoulder 29 of the trigger (as shown in Fig. 2) and thus prevents any possible movement of 100 said trigger and sear for releasing the hammer. In this way, the firing mechanism is effectively 105 blocked from operation.

A lower portion 30 of the safety device is extended downwardly through a slotted portion of 110

the trigger guard 2 and when the safety device is at its "on" position (as shown in Fig. 2) the portion 30 extends into the space normally occupied by the finger in pressing the trigger. This position of the portion 30 will serve as a warning to the marksman that the safety is "on" when he attempts to place his finger on the trigger for firing. In other words, when the safety device is adjusted to "off" position, the extending portion 30 is substantially housed in the fore part of the trigger guard (as shown in Fig. 1) thus leaving the trigger guard opening free for the insertion of the finger in firing, but when adjusted to its "on" position the extension 30 sufficiently closes the trigger guard opening (as shown in Fig. 2) to thereby prevent the entrance of the finger therein for being placed in front of the trigger to fire. A forward knurled portion or knob 31 of said safety device is also provided which extends somewhat beyond the trigger guard 2 when the safety device is in its "off" position, whereby a pressure backwardly thereon will set the safety device into its "on" position.

It will thus be seen that the safety device may be conveniently thrown to its "on" position by pressing backwardly on knob 31 and restored to its "off" position by pushing downwardly on the lower portion 30; and that it is held in either of its adjusted positions by the pressure of the firing base 20 bearing against the same through

its cam surface 27. It is simple and effective both in blocking the firing mechanism against action and in warning the marksman of its position.

What I claim is:

1. In a firearm the combination with a firing mechanism including a trigger and firing spring, of a safety device pivoted in the fore-part of the trigger guard for being adjusted into "on" and "off" positions, said device comprising a finger portion for extension into the space normally occupied by the finger in pressing the trigger, and also comprising a shoulder for blocking the firing mechanism against firing movement, and a firing spring actuated member arranged to yieldingly hold said safety device in its adjusted positions. 80 85 90

2. In a firearm, the combination with a firing mechanism including a hammer, firing spring therefor and a trigger, of a safety device mounted for adjustment into "on" and "off" positions comprising means for blocking the firing mechanism from operation when adjusted into its "on" position, and means whereby said single firing spring serves to operate said hammer, to return said trigger after being pulled for firing and to yieldingly hold said safety device in either of its adjusted "on" or "off" positions. 95 100
